SAMUEL SAILOR, OF PHILADELPHIA, PENNSYLVANIA, ASSIGNOR TO
MARCH, SISLER & CO., OF LIMERICK STATION, PENNSYLVANIA.

Design No. 2,749, dated August 13, 1867.

DESIGN FOR A STOVE-DOOR.

The Schedule referred to in these Letters Patent and making part of the same.

TO ALL WHOM IT MAY CONCERN:

Be it known that I, SAMUEL SAILOR, of the city of Philadelphia, in the State of Pennsylvania, have invented or produced a new and original ornamental Design for the Plates of a Stove; and I do hereby declare at the following is a full, clear, and exact description of the same, reference being had to the accompanying drawing, making a part of this specification, and to the letters of reference marked thereon.

The nature of my design consists of a series of ornamental figures around and in connection with an oval border in bas-relief on a flat plane, as shown in the drawing; A B being the ornamental figures, C D the oval border, and E the flat plane.

What I claim as my invention, and desire to secure by Letters Patent, is—
The design for stove-plates herein set forth and shown.
